PERFUME DISPENSER

Zyga S. Taube, Los Angeles, Calif., assignor to Kimberly Corporation, Culver City, Calif., a corporation of California

Application January 27, 1951, Serial No. 208,180

8 Claims. (Cl. 15—132.7)

The present invention relates to improvements in perfume dispensers, designed to permit application of minute quantities of perfume to the skin or hair by rolling contact of a feeding ball with the skin. The invention is particularly directed to a construction which is simple, economical and effective, the perfume-distributing ball also acting as a seal or closure to the container in which perfume is stored.

The design of a perfume dispenser must take into consideration the volatility of the perfume and the readiness with which such perfume seeps through minute openings. Moreover, many perfumes upon evaporation leave gummy residues which tend to clog minute orifices. In actual use, a dispenser should be capable of ejecting, liberating or feeding very minute quantities of perfume. The cost of the device must be small.

In order to prevent evaporation losses and insure the discharge of but minute quantities of perfume, prior devices have employed fine capillary discharge ports, but such small-diameter ports are readily clogged, rendering the device ineffective. In other instances, devices have been provided with threaded caps which applied sealing gaskets to the discharge apertures, but this expedient is not satisfactory since the threading and unthreading of a cap is time-consuming, generally involves the use of two hands and such caps are often lost. Other perfume dispensers employing pistons and atomizing nozzles have been designed heretofore, but these devices are too expensive to appeal to the general buying public.

The present invention utilizes a rolling ball as an applicator, it being well known in the writing instrument art that a rolling ball can feed small quantities of liquid to a desired surface. Ball-pointed writing instruments are well known in the art and various constructions have been shown in old patents, such as United States Letters Patents No. 853,156, No. 894,488 and No. 1,563,408. Although in general, the concept of using a rolling ball for the application of a film of liquid is not new, it has been found that the constructions heretofore employed in the manufacture of writing instruments employing a rolling ball are totally unsuited to the distribution of a volatile, penetrating liquid such as an alcoholic perfume. Furthermore, the prior constructions, as exemplified by writing instruments, are complex and expensive and no provision exists therein for completely sealing the contents of the dispenser against leakage of the liquid contents when the device is not in use. On the contrary, most ball-pointed writing instruments include an air access hole leading to the chamber in which the body of ink is kept. Such aperture or hole would destroy the utility of a perfume dispenser.

The device of the present invention utilizes a feeding assembly construction in which the resiliency of the materials employed plays an important part. A unitary housing is provided, such housing terminating in an aperture leading into a spherical recess. The integral wall of such recess is defined by a reticulated resilient partition integral with the housing. A ball retained within

2

the spherical recess is normally seated against the housing by the pressure of a spring acting against the resilient partition upon which the ball rests. Such seating occurs in a spherical zone adjacent the port and normally serves to seal the housing against the escape of perfume vapors. External pressure against the ball unseats the ball from the sealing zone for rotation within the recess, the ball conveying on its surface liquid supplied through the reticulated partition for deposit upon the surface of the skin by rolling contact of the ball. When pressure is relieved by removal of the dispenser from contact with the skin surface, a spring within the container biases the partition and the ball forwardly into seating contact with the sealing zone.

15 An object of this invention is to design and provide a self-closing, self-sealing dispenser for perfume or a volatile liquid operable in a novel manner.

Another object of this invention is to design and provide a dispenser for volatile liquid wherein minute quantities of the liquid are deposited upon a surface by pressure-contact of a rolling ball which conveys liquid from a supply within the dispenser.

20 A further object of this invention is to design and provide a perfume dispenser wherein minute quantities of perfume are effectively and efficiently deposited upon a selected surface and wherein the housing for the perfume is immediately and automatically sealed upon removal of the dispenser from contact with the surface to which the perfume is being applied.

25 A further object of this invention is to provide a perfume dispenser wherein a resilient elastic construction retains a rigid ball in sealing relation to a ported end of the dispenser, said ball being operable under external pressure to be inwardly displaced for rolling contact with a surface.

30 Another object of this invention is to provide a relatively friction free cradle or ball seat for the perfume dispensing ball when the ball is in rolling contact with a surface for smoothly and uniformly dispensing perfume.

35 40 Other objects and advantages of this invention will be readily apparent to those skilled in the art from the following description and drawings:

Fig. 1 is a perspective view of a perfume dispenser embodying this invention.

45 Fig. 2 is a longitudinal sectional view of the dispenser shown in Fig. 1, the section being taken in a plane bisecting the dispenser as indicated by line II—II of Fig. 1.

50 Fig. 3 is a fragmentary view of the perfume-dispensing end in sealed and closed relationship, the section being taken in the plane indicated by line III—III of Fig. 2.

55 Fig. 4 is an enlarged fragmentary view of the perfume-dispensing end in open operative relationship for dispensing liquid upon a surface.

Fig. 5 is a sectional view taken in a transverse plane indicated by line V—V of Fig. 3.

60 In the drawings which illustrate an embodiment of the invention, a perfume dispenser generally indicated at 10 comprises an integral one-piece hollow tubular cylinder or housing 11 preferably made as by an injection molding of a suitable polyethylene material having characteristics of resiliency and elasticity. A continuous one-piece integral wall 12 of cylinder 11 may be provided with a uniform section throughout almost its entire length. At a feeding assembly or perfume dispensing end 13, wall 12 may be provided with a somewhat thicker

65 section to provide an external annular shoulder 14. An outer casing 15 may seat against said shoulder 14 and may enclose the cylindrical portion of the cylinder. An annular outwardly projecting rib 15a cooperates with a complementary annular groove in the casing to secure

70 the casing on the cylinder 11.

The thicker wall section of end 13 may be smoothly

curved inwardly toward the axis of the cylinder to provide a bullet-shaped end. The inwardly curved wall terminates in an annular resilient lip portion 16 defining a port 17 coaxial with the cylinder.

Integrally formed with end 13 is a perforated or reticulated transverse resilient partition 18 spaced inwardly from port 17. The partition 18 comprises intersecting webs 19 defining apertures 20; said webs 19 being integrally formed with the wall of end 13 adjacent to lip portion 16.

A ball-receiving recess 21 is provided by lip portion 16 and partition 18; said recess having smooth, spherical surfaces extending over an area of greater than 2 pi steradians but less than 4 pi steradians. Such construction provides for the center of the spherical surface of the recess to be spaced inwardly from port 17 so that the inner surface of lip portion 16 is curved inwardly toward the axis of the cylinder to provide a spherical sealing zone.

A rigid smooth surfaced ball 22, having a spherical radius of virtually the same dimension as the radius of the spherical surfaces of the recess, is received within said recess. The ball 22 may be inserted by forcing the ball into the recess, the material of the lip portion 16 being sufficiently resilient and elastic to expand to allow the ball to be thus inserted. When the ball is positioned within the recess the lip portion 16 resiliently contracts and snugly and closely contacts a spherical zone of the ball in sealing relation outwardly of the center of the spherical recess.

The partition 18 is biased outwardly against ball 22 by spring means 23, said spring means 23 having an end turn 24 seated against partition 18 and positioned thereon by an inwardly extending boss 25. The spring means 23 also serves to urge the ball into sealing relation with inner surface of lip portion 16. The opposite end of spring means 23 may be seated against a bottom wall 26 of a cup-shaped plug 27, said plug having a cylindrical portion closely fitting against internal surfaces of the opposite end of cylinder 11 to close open end 28 thereof.

Due to the resiliency and elasticity of the material of the molded housing, creation of internal pressures during assembly and filling should be avoided. An exemplary procedure for assembling and filling the dispenser may comprise positioning spring 23 within the cylinder through open end 28 and sealing end 28 by inserting plug 27 until spring 23 is lightly compressed against the resilient partition 18. A selected amount of perfume fluid is then injected into the cylinder through recess 21. The ball 22 may then be forcibly inserted into the recess 22 and sealably engages the lip portion 16 to releasably seal the perfume fluid. Plug 27 entirely seals open end 28. No air vent is provided because such a vent would obviously permit continuous volatilization of perfume carried within the cylinder.

The ball 22 and the resilient elastic construction of the lip portion 16 and transverse partition 18 provide a self-closing, self-sealing means for the perfume dispensing end of the dispenser 11. In closed and sealed relation the lip portion 16 tightly embraces a spherical sealing zone on ball 22. The spring means 23 biases the transverse partition 18 forwardly to facilitate the sealing action of lip portion 16.

When it is desired to apply perfume to a skin surface, application of external pressure upon the dispenser effected by pressing ball 22 against a selected area of skin surface causes the ball to move axially inwardly against the action of the spring means 23 and the resilient elastic partition 18. Such axial inward displacement of ball 22 permits the ball to rotate within recess 21 and to convey liquid on the ball surface to the skin surface to which it is being applied. The surface of the rolling ball is provided continuous wetting contact with perfume liquid through the apertures 20 in the reticulated partition 18. As the ball rolls in its contact with the skin

surface minute quantities of liquid carried by the ball surface are conveyed to port 17 and then deposited upon the skin surface.

It will be readily apparent that when the applying pressure is relieved, as when the dispenser is removed from contact with a skin surface, the spring means 23 and resilient partition 18 cause the ball to be displaced axially outwardly so that the lip portion 16 engages the ball in a spherical sealing zone which prohibits escape of perfume liquid or volatilized liquid carried within the dispenser.

The relationship of the ball 22, resilient partition or web 18, and the spring 23 should be particularly noted. The resilient partition 18 serves to provide a relatively friction-free, smooth-surfaced cradle for the ball to roll in when the ball contacts the skin while dispensing perfume. Thus the ball may freely rotate even though the spring is exerting an outwardly directed pressure against the partition. Such free rotation results in a smooth and uniform dispensing action.

The partition 18 also serves to restrain or temper the amount of outwardly directed pressure transmitted from the spring to the ball by the resiliency of the partition material and by distribution of stress to the integral encircling thick inwardly curving wall section of end 13. The resilient partition thus transmits sufficient force to the ball for sealing contact with the lip portion, but also acts as a control or dampening means to said spring forces which might cause cold flow of the lip portion and 30 eventual ejection of the ball from the recess, a condition which would occur if the spring were directly acting on the ball.

The perfume dispenser described above thus provides a means for smoothly and uniformly applying minute quantities of perfume liquid to selected areas of a skin surface without loss of such liquid to areas where deposit of perfume is not desired (as in a perfume atomizer). The perfume dispenser of this invention is capable of applying minute quantities of perfume without waste because of the direct positive contact of the perfume liquid conveying ball with the desired selected surface.

It is understood that other resilient and elastic materials may be employed to provide a resilient self-sealing, self-closing perfume liquid feeding assembly, and that other means may be used for retaining and positioning the rigid ball in operative relationship with the port.

All other modifications and changes of the above described embodiment coming within the scope of the appended claims are embraced thereby.

I claim:

1. A perfume dispenser comprising: a preformed hollow cylinder provided with a closure member at one end and having its wall curving inwardly toward the axis of the cylinder to form a bullet shaped portion at the other end; a reticulated transverse partition integral with said bullet shaped end portion; a preformed recess within the bullet shaped portion defined by walls of the cylinder and the reticulated partition, the internal surface of the recess being spherical, smooth and extending over a solid angle of over 2 pi steradians but less than 4 pi steradians and terminating in a marginal sealing zone; a port, axially positioned with respect to the cylinder, leading into the recess; the wall of the cylinder being resilient and elastic, in the region of the spherical recess, to permit passage of a virtually rigid ball into said recess through said port and to grasp said ball by the marginal sealing zone; the reticulated transverse partition being resiliently elastic and arranged to be inwardly deflected by application of pressure on the ball within the recess to allow rotation of the ball in the recess out of sealing contact with the sealing zone and the conveyance of liquid supplied to the surface of the ball to the port; and spring means, within the cylinder, biasing the partition into contact with the ball to normally seat the latter against the inner surface of the wall of the recess.

2. A perfume dispenser comprising: a preformed hollow cylinder having its wall curving inwardly toward the axis of the cylinder to form a bullet shaped end portion, a closure member for the opposite end portion of the cylinder; a reticulated transverse partition integral with said bullet shaped end portion; a preformed recess within the bullet shaped portion defined by walls of the cylinder and the reticulated partition, the internal surface of the recess being spherical; a port, axially positioned with respect to the cylinder, leading into the recess; the wall of the cylinder being resilient and elastic, in the region of the spherical recess, to permit passage of a virtually rigid ball into said recess through said port and to sealingly retain said ball against outward displacement; the reticulated transverse partition being resiliently elastic and arranged to be inwardly deflected by application of pressure on the ball within the recess to allow rotation of the ball in the recess and conveyance of liquid supplied to the ball through reticulations of the partition by said ball to the port, said resilient elastic partition normally biasing the ball outwardly into seating contact with the inner surface of the wall of the cylinder adjacent said port.

3. A perfume dispenser comprising: a preformed hollow cylinder having its wall curving inwardly toward the axis of the cylinder to form a bullet-shaped end portion, a closure member for the opposite end portion of the cylinder; a reticulated transverse partition integral with said bullet-shaped end portion; a preformed recess within the bullet-shaped portion defined by walls of the cylinder and the reticulated partition, the internal surface of the recess being spherical, smooth and extending over a solid angle of over 2π steradians but less than 4π steradians; a port, axially positioned with respect to the cylinder, leading into the recess; a virtually rigid ball retained in said recess, the inwardly curved wall of the cylinder being resilient and elastic; the reticulated transverse partition being resiliently elastic and arranged to be inwardly deflected by application of pressure on a ball within the recess to allow rotation of the ball in the recess and the conveyance of liquid supplied to the ball through reticulations of the partition, by said ball to the port; and spring means within the cylinder biasing the partition into contact with the ball to seal and to close the port by contact of the ball with the inwardly curved wall of the cylinder.

4. A self-closing, self-sealing dispenser for perfume adapted to deposit minute quantities of perfume upon a surface by rolling pressure contact, comprising: a preformed, unitary, hollow tubular housing provided at one end with a closure member and at the other end with a coaxial port defined by an encircling inwardly curved resilient lip portion; a perforated transverse resilient partition inwardly of said port and integral with said lip portion; a preformed recess defined by said partition and said lip portion, the surfaces of said recess being spherical and extending over a solid angle of greater than 2π steradians but less than 4π steradians; a virtually rigid smooth surfaced ball within said recess having a radius corresponding to the radius of the spherical surfaces of said recess; spring means within the housing biasing the partition into pressure contact with the ball to normally seat said ball against the inner surface of the lip portion to close said port along a spherical sealing zone; said partition being inwardly deflected by application of external pressure on the ball to allow rotation of the ball in the recess and to space said sealing zone from the ball, liquid being supplied to the ball through the perforations of the partition and carried by rotation of the ball to the port for deposit on a surface to which the liquid is to be applied.

5. A self-closing, self-sealing dispenser for perfumes adapted to deposit minute quantities of perfume upon a surface by rolling pressure contact, comprising: a preformed, unitary, hollow tubular housing provided at one

end with a closure member and at the other end with a coaxial port defined by an encircling resilient elastic inwardly curved lip portion; a perforated resilient elastic transverse partition inwardly of said port and integral with said lip portion; a preformed recess defined by said partition and said lip portion, the surfaces of said recess being spherical; a virtually rigid smooth surfaced ball within said recess having a radius corresponding to the radius of the spherical surfaces of said recess; spring means within the housing biasing the partition into pressure contact with the ball to normally seat said ball against the inner surface of the resilient lip portion to close said port along a spherical sealing zone; said resilient partition being inwardly deflected by application of external pressure on the ball to allow rotation of the ball in the recess out of sealing contact with the sealing zone, liquid being supplied to the ball through the perforations of the partition and carried by rotation of the ball to the port for deposit on a surface to which the liquid is to be applied.

6. In a self-closing, self-sealing dispenser for volatile liquids comprising: a preformed housing provided with a closure member at one end and provided with a port defined by an encircling inwardly curved resilient lip portion, said lip portion having an internal arcuate surface forming a spherical zone; a virtually rigid smooth ball normally biased into sealing contact against said arcuate surface to close said port; and resilient means within the housing retaining said ball in operative relationship with said port said resilient retaining means including an elastic means integral with said housing and having a surface merging with said arcuate surface to form a recess virtually complementary to a portion of said ball; said ball being rotatable by application of external pressure thereto for spacing the arcuate surface from the ball and for conveying liquid within the housing on the face of the ball for deposit upon a selected surface.

7. In a self-closing, self-sealing dispenser for volatile liquids comprising: a preformed housing provided with a closure member at one end and provided with a port defined by an encircling inwardly curved resilient lip portion, said lip portion having an internal arcuate surface forming a spherical zone; a virtually rigid smooth ball normally biased into sealing contact with said arcuate surface to close said port; and resilient means within the housing retaining said ball in operative relationship with said port, said resilient means including a perforated resilient partition integral with the housing and provided with spherical surfaces defining with said arcuate surface a partially spherical recess; said ball being rotatable by application of external pressure thereto for spacing the arcuate surface from the ball and for conveying liquid within the housing on the face of the ball for deposit upon a selected surface.

8. In a self-closing, self-sealing dispenser for volatile liquids, the combination of: a preformed molded housing provided with a closure means adjacent one end and provided with a port defined by an encircling, inwardly curved resilient lip portion, said lip portion having an internal arcuate surface forming a spherical zone; a perforated resilient partition integral with the housing and adjacent to the lip portion, said partition having spherical surfaces smoothly merging with the internal arcuate surface of the lip portion to provide a partially spherical recess; a virtually smooth, rigid ball having a radius virtually corresponding to the radius of the spherical recess held in said recess between said lip portion and said partition and resiliently grasped thereby, said ball being normally biased outwardly to sealingly contact said arcuate surface along said spherical zone, said ball being rotatable by application of external pressure thereto to displace said ball inwardly against said resilient partition to break the seal at said spherical zone and to allow virtually unobstructed conveyance of liquid on the sur-

face of the ball to the port for deposit upon a selected surface.
